UNITED STATES PATENT OFFICE

118,960

DESIGN FOR A COMBINED RADIO AND PHONOGRAPH CABINET

Frederick A. Kolmetz, New York, N. Y., assignor
to Liberty Music Shops, Inc., New York, N. Y.,
a corporation of New York

Application October 18, 1939, Serial No. 87,707

Term of patent 14 years

To all whom it may concern:

Be it known that I, Frederick A. Kolmetz, formerly a citizen of Latvia, who has made application for citizenship in the United States of America, residing in the Borough of Queens, county of Queens, city and State of New York, have invented a new, original, and ornamental Design for a Combined Radio and Phonograph Cabinet, of which the following is a specification, reference being had to the accompanying drawing forming part thereof, wherein:

Figure 1 is a perspective view of the combined radio and phonograph cabinet embodying my new design.

Fig. 2 is a top plan view of the same.

The side opposite that shown in Fig. 1 is the same as illustrated. The opposite ends of the cabinet are also alike.

I claim:

The ornamental design for a combined radio and phonograph cabinet, as shown and described.

FREDERICK A. KOLMETZ.
